UNITED STATES PATENT OFFICE.

ARTHUR O. AUSTIN, OF BARBERTON, OHIO, ASSIGNOR TO AMERICAN NARROW FABRIC COMPANY, OF WORCESTER, MASSACHUSETTS, A CORPORATION OF MASSACHUSETTS.

INSULATOR PIN.

Original application filed May 12, 1920, Serial No. 380,826. Divided and this application filed March 25, 1926. Serial No. 97,187.

This invention relates to pins for supporting insulators for various electrical conductors, and has for its object the provision of devices of the class named which shall be of improved construction and operation.

The invention is exemplified in the combination and arrangement of parts shown in the accompanying drawings and described in the following specification, and it is more particularly pointed out in the appended claims.

In the drawings—

Fig. 1 is an elevation of one embodiment of the invention with parts in section;

Fig. 2 is an elevation with parts in section of a slightly different form of the invention; and

Fig. 3 is a similar view of another modification of the invention.

This is a division of application, Serial No. 20 380,826, filed May 12, 1920, Patent Number 1,657,340, dated January 24, 1928.

Insulators for electrical conductors are supported in a variety of ways, one of the common means being by the use of pins carried by the supporting structure and bearing the insulator fitted over the end thereof. Such pins are used for supporting insulators on metal and wooden arms and pole tops and also on various constructions other than regular line wire supports. A pin to meet the requirements to which it is subjected must have the necessary mechanical strength to withstand the stresses brought upon it and should not materially lower the flashover voltage of the insulator or otherwise diminish the electrical efficiency of the insulator. The cost of manufacture should be kept as low as possible and the pin should provide the required strength without setting up undue stress in the fragile material of the insulator which it carries. The pin should also be adaptable to various conditions which arise in line construction and other electrical installations where insulators are used, and it is also desirable that the pins should be so designed that a large variety can be made from as small a variety of stock as possible.

From the various embodiments of the invention shown in the drawings, it will be apparent that the small body diameter of pins constructed in accordance with this invention permits developing the maximum flashover voltage value of the insulator since the small diameter of the pin body keeps the outer

surface of the body at a maximum distance 55 from the lower edge of the insulator itself. It will also be seen that the supporting base and the body portion of the insulator pin are made in separate parts which permits the use of a base having sufficient area so that the 60 cross-arm upon which the base rests will not be crushed under bending moment. The construction permits of a balanced arrangement and at the same time does not sacrifice the electrical properties of the insulator. In pins 65 having a small base formed integrally with the pin, the bending moment upon the pin forces the edge of the base into contact with the upper face of the supporting structure so that where the structure is made of wood, 70 the fibres are crushed at the edge of the base, permitting the pin to lean to one side and loosening the connection with the support. It is impractical to form a pin with an integral base of sufficient area to overcome this 75 difficulty, for the reason that if the pin is cut from a piece of stock of large diameter the waste is too great to justify a sufficient expanse of base, and if it is undertaken to upset or swage a smaller piece of stock to form 80 the base, it is impossible to expand the material a sufficient amount to give a base of the required extent. Such operation also tends to form laps or flaws in the metal. Where the base is formed separately from the pin and is 85 provided with means to hold the two rigidly together, when the pin is installed, the base may be made of any desired extent and shape and pins may be standardized so that the same pins may be used with a large variety of 90 supporting bases. A pin may be secured to the base by means of a tapered end fitting in a tapered socket and the taper may be so proportioned that the pins may be readily made with a swaging-machine from straight- 95 bar stock without the loss of material. No finishing operation is necessary other than the swaging process in order to obtain a good fit for the base. The taper should be such that the pin will not tend to lift out of the base when a bending moment is applied, and at the same time the taper should preferably be such that the pin will not bend in the small sections, the smaller portion of the pin being reinforced by the base. When the base and body are assembled they are held together so that they will work as a unitary structure and the main body of the pin may be made in

straight section or given a taper which will give uniform strength for the bending moment, or it may be made in stepped diameters, if desired.

- 5 The insulator may be secured to the pin in a large variety of ways, depending upon conditions. In some cases a lead tip may be cast or pressed on the pin which will form a cushion between the hard metal and the porcelain.
- 10 The upper portion of the pin may, under some conditions, be provided with a roughened surface, or with resilient flanges or projections, to reduce the danger of cracking the insulator under expansion and contraction of 15 temperature changes. Another method of securing the insulator to the top of the pin is to provide the end of the pin with large or small threads which can be adapted to a thimble of sheet material threaded into the 20 insulator. In this construction the threaded parts may be cone-shaped and the insulator may be tightened down firmly and afterwards the wire groove in the insulator may be properly aligned by turning the pin relative to its 25 supporting base. The thimbles, however, instead of being cone-shaped may be cylindrical, so that they can be turned upon the pins to align the wire grooves without loosening the insulator on the pin. Where this arrangement is made, the pin can be rigidly attached 30 to the supporting base. Under most conditions, however, the pin and base will be separable which will permit combinations of various forms of pins with different kinds of 35 bases so that the proper arrangement may be secured for a large variety of conditions.
- In Fig. 1 a composite pin is shown comprising a central rod 51 having an outer strengthening tubular shell 52 surrounding the rod. 40 The rod and shell each forms a reinforcement for the other and the two co-operate to form an exceedingly strong pin. The shell 52 is pressed into shape from a straight tubular member and at the same time secured in place 45 upon the central rod 51. The compression of the tubular member to form a taper will, of course, cause a gradual thickening of the wall of the pin from the top of the base portion to the top of the pin, as shown in the 50 drawing. Depressions 53 may be previously formed in the rod 51 at the points of contact between the rod and the shell, so that the metal of the shell will be forced into the depressions during the forming operation and thus insure firm connection between the rod 55 and the outer shell. The lower end of the shell is tapered, as shown at 54, for engaging a tapered socket member 59 and the ends of the rod 51 are threaded, as shown at 55 and 60 56, for connection with means for securing the pin on its support and with means for securing the insulator upon the pin, respectively.

In Fig. 2 a pin is shown similar to that 65 illustrated in Fig. 1, except that a portion of

the central rod is omitted leaving only short pieces 61 and 62 at the upper and lower ends of the pin respectively. Where this construction is used, the tubular member 63 is made of sufficient strength to withstand the stresses 70 to which the pin is subjected.

In Fig. 3 the pin 1 is formed of a tubular member 84 pressed or swaged into the proper shape and tapered to fit a socket member 85 formed on a base 86. An internal reinforcing sleeve 87 is arranged within the tubular member 84 to strengthen the pin adjacent the base and to provide material for a threaded opening for receiving the threaded end of a bolt 88. Where the lower ends of the pins are 80 threaded for receiving the threaded ends of standard bolts, it will be apparent that the pins may be secured to various sizes of cross-arms by merely substituting bolts of different standard lengths. 85

I claim:

1. An insulator pin comprising a tubular member having a body portion tapered towards its upper end, an oppositely tapered base portion and a support for said tubular member having a tapered socket therein for receiving said tapered base portion and having a flange extending radially from said base portion, the opening in said body portion being also tapered toward the upper end of said pin. 90

2. An insulator pin comprising a tubular member having an elongated body portion tapered toward its upper end, the opening in said body portion being also tapered toward the upper end, a shorter oppositely tapered base portion, a supporting base having a tapered socket therein for receiving said base portion, and a reinforcing member disposed within said base portion, the opening in said body member being larger than said reinforcing member at the junction of said body and base portions. 100

3. An insulator pin comprising a tubular member having the opposite ends thereof swaged inwardly to provide an upwardly tapering elongated body portion and a lower oppositely tapered base portion with the maximum diameter of said pin at a point adjacent the top of said base portion, the walls of said tubular member being gradually thickened from the point of maximum diameter toward the top of said pin, and a support for said tubular member having a tapered socket therein for receiving said tapered base portion and having a flange extending radially from said base portion. 110

4. An insulator pin comprising a tubular member having an elongated upper body portion tapered inwardly toward the top thereof, a base portion tapered inwardly toward the bottom thereof, and a reinforcement disposed within said base portion and tightly held in place therein by the walls of said base portion, said walls being spaced away 120 125 130

from said reinforcement between the ends of said pin.

5. An insulator pin comprising a tubular member having a central reinforcing rod extending therethrough, said tubular member being fixedly secured to said rod against relative longitudinal movement of said rod and member at opposite ends of said tubular member and spaced away from said rod between

10 said ends.

6. An insulator pin comprising a tubular member having a reinforcing rod extending therethrough, said tubular member being spaced outwardly from said rod intermediate

15 the ends of said tubular member and tapered inwardly into contact with said rod at opposite ends of said tubular member.

7. An insulator pin comprising a tubular member having a reinforcing rod extending

20 therethrough, the wall of said tubular member being spaced from said rod intermediate the ends of said tubular member but tapered inwardly to engage said rods at opposite ends of said tubular member, the upper tapered

25 end of said tubular member being longer than the lower tapered end thereof.

8. An insulator pin comprising a tubular member having a reinforcing rod extending therethrough, said tubular member being spaced outwardly from said rod intermediate

30 the ends thereof but tapered inwardly to engage said rod at opposite ends of said tubular member, and a supporting base engaging the lower tapered end of said tubular member,

35 said rod being extended beyond said tubular member at the opposite ends thereof.

9. An insulator pin comprising a tubular member having a reinforcing rod extending therethrough, said tubular member being

40 tapered inwardly toward the opposite ends

thereof, a supporting base for receiving the lower tapered end of said tubular member, and having the upper extremity thereof substantially registering with the maximum diameter of said tubular member, said tubular member being spaced outwardly from said rod at the point of maximum diameter of

45

said tubular member.

10. An insulator pin comprising a tubular member having a reinforcing rod extending

50 therethrough, said rod having irregularities on the surface thereof adjacent opposite ends of said tubular member, said tubular member being swaged inwardly to engage said rod and to conform to the irregularities on the

55

surface thereof to provide firm connection between said tubular member and rod at opposite ends of said tubular member, said tubular member being spaced outwardly from said rod intermediate the points of connection with said rod and being gradually tapered toward the opposite ends of said tubular member from an intermediate point.

11. An insulator pin comprising a tubular member having a reinforcing rod extending

60 therethrough, said tubular member being spaced outwardly from said rod at a point between the ends of said tubular member and gradually tapered toward said tubular member at opposite sides of said point and closely

65

70 engaging said rod at the ends of said tubular member, said rod being extended beyond said tubular member, and a supporting base having a socket receiving the lower tapered end of said tubular member.

75

In testimony whereof I have signed my name to this specification on this 20th day of March, A. D. 1926.

ARTHUR O. AUSTIN.

CERTIFICATE OF CORRECTION.

Patent No. 1,690,392.

Granted November 6, 1928, to

ARTHUR O. AUSTIN.

It is hereby certified that the above numbered patent was erroneously issued to "American Narrow Fabric Company, of Worcester, Massachusetts, a corporation of Massachusetts", whereas said patent should have been issued to "The Ohio Brass Company, of Mansfield, Ohio, a corporation of New Jersey", said corporation being assignee by mesne assignments of the entire interest in said invention, as shown by the records of assignments in this office; and that the said Letters Patent should be read with this correction therein that the same may conform to the record of the case in the Patent Office.

Signed and sealed this 11th day of December, A. D. 1928.

(Seal)
